ROTATABLE DISPLAY STAND FOR GREETING
CARDS OR THE LIKE

Herbert Schwartz, Milburn, N.J.

Filed Nov. 6, 1959, Ser. No. 58,242

Term of patent 14 years

(Cl. D80—9)

Fig. 1.

Fig. 2.

Fig. 3.

Fig. 1 is a front perspective view taken from the right side of a rotatable display stand for greeting cards, or the like embodying my new design;

Fig. 2 is a rear perspective view taken from the left side thereof; and

Fig. 3 is a top plan view thereof on a reduced scale. I claim:

The ornamental design for a rotatable display stand for greeting cards or the like, as shown.
